US0D1108978S

(12) **United States Design Patent** (10) **Patent No.:** **US D1,108,978 S**
(45) **Date of Patent:** **** Jan. 13, 2026**

(54) **BOTTLE**

(71) Applicant: **Kraft Foods Group Brands LLC**,
Chicago, IL (US)

(72) Inventors: **Anna Leigh Prochaska**, Chicago, IL (US); **Peter Clarke**, Newtown, CT (US); **Stuart Leslie**, Larchmont, NY (US); **Luis Ramiro Gutierrez Montenegro**, Stamford, CT (US); **Eric Hartman**, Ridgefield, CT (US); **Taek Kim**, Township of Washington, NJ (US); **Trond Erik Tollefsen**, Orpington (GB); **Chi Cheong Lau**, Nottingham (GB)

(73) Assignee: **Kraft Foods Group Brands LLC**,
Chicago, IL (US)

(**) Term: **15 Years**

(21) Appl. No.: **29/899,769**

(22) Filed: **Aug. 11, 2023**

(51) LOC (15) Cl. **09-01**

(52) U.S. Cl.

USPC **D9/560**

(57) **CLAIM**

The ornamental design for a bottle as shown and described.

DESCRIPTION

FIG. 1 is a front perspective view of a bottle, showing my new design;

FIG. 2 is a front elevation view of the bottle of FIG. 1;

FIG. 3 is a rear elevation view of the bottle of FIG. 1;

FIG. 4 is a left-side elevation view of the bottle of FIG. 1;

FIG. 5 is a right-side elevation view of the bottle of FIG. 1;

FIG. 6 is a top plan view of the bottle FIG. 1; and,

FIG. 7 is a bottom plan view of the bottle of FIG. 1.

The broken lines in the figures illustrate the portions of the bottle and form no part of the claimed design.

The broken lines on the bottle in FIGS. 1-3 and 7 are included to show unclaimed surface lines on the article.

1 Claim, 6 Drawing Sheets
